US00D773374S

(12) **United States Design Patent** (10) **Patent No.:** **US D773,374 S**
Braver et al. (45) **Date of Patent:** **** Dec. 6, 2016**

(54) **BOAT CONSOLE**

(71) Applicants: **Skip Braver**, Miami, FL (US); **Hector Rodriguez**, Miami, FL (US); **Sidney Lanier**, Cape Coral, FL (US)

(72) Inventors: **Skip Braver**, Miami, FL (US); **Hector Rodriguez**, Miami, FL (US); **Sidney Lanier**, Cape Coral, FL (US)

(73) Assignee: **Cigarette Racing Team, LLC.**, Opa Locka, FL (US)

(**) Term: **14 Years**

(21) Appl. No.: **29/508,578**

(22) Filed: **Nov. 7, 2014**

Related U.S. Application Data

(63) Continuation-in-part of application No. 29/445,749, filed on Feb. 15, 2013, now Pat. No. Des. 717,226.

CLAIM

The ornamental design for a boat console, as shown and described.

DESCRIPTION

FIG. 1 is a top perspective view illustrating my design for a boat console;

FIG. 2 is yet another top perspective view thereof;

FIG. 3 is a left side view thereof;

FIG. 4 is a right side view thereof;

FIG. 5 is a top view thereof;

FIG. 6 is a front view thereof; and,

FIG. 7 is a rear view thereof.

The broken lines illustrate portions of the article that form no part of the claimed design.

1 Claim, 7 Drawing Sheets
